UNITED STATES PATENT OFFICE.

ALEXANDER ZECK AND FREDERICK VAN ZECK, OF GRAFTON, WEST VIRGINIA.

HEATING APPARATUS.

No. 919,110.

Specification of Letters Patent.

Patented April 20, 1909.

Application filed May 15, 1908. Serial No. 433,011.

To all whom it may concern:

Be it known that we, ALEXANDER ZECK and FREDERICK VAN ZECK, both citizens of the United States, and residents of Grafton, 5 in the county of Taylor and State of West Virginia, have invented a new and Improved Heating Apparatus, of which the following is a full, clear, and exact description.

The invention relates to heating apparatus, 10 such as shown and described in the Letters Patent of the United States, No. 880,954, granted to us on March 3, 1908.

The object of the present invention is to provide a new and improved heating apparatus 15 in which steam and hot water heating is combined in a very simple and effective manner.

The invention consists of novel features 20 and parts and combinations of the same which will be more fully described herein-after and then pointed out in the claims.

A practical embodiment of the invention is represented in the accompanying drawings forming a part of this specification, in which 25 similar characters of reference indicate corresponding parts in both views.

Figure 1 is a sectional side elevation of the improvement; and Fig. 2 is an enlarged longitudinal central section of the fitting attached to the front radiator section.

The hot water radiator illustrated in Fig. 1 consists of a front or inlet section A, a rear or overflow section B and intermediate sections C interposed between the sections A and B.

35 The upper end of the inlet section A is connected with a steam pipe D having a valve E and leading from the boiler or other source of steam supply. The lower end of the inlet section A is connected by an opening F with

40 the lower end of the adjacent intermediate section C, and the intermediate sections C are connected with each other at their lower ends by openings F'. The upper end of the inlet section A is connected by an opening G with the adjacent intermediate section C, and

45 the several intermediate sections C are connected with one another at their upper ends by openings G', and the last intermediate section C is connected with the overflow section B by an opening G². The bottoms of

50 the several openings G, G' and G² are on the same level.

A plug H is arranged in the walls between the overflow section B and the rear intermediate section C near the lower ends thereof and in this plug H is secured one end of a re-

turn water pipe I extending through the openings F' and F and connecting at its other end with a fitting J secured to the lower end of the inlet section A. The fitting J is provided with a discharge compartment J' and a drainage compartment J², and the said discharge compartment J' is connected with a pipe K for returning the water of condensation to the boiler. In the bottom of the 60 compartment J² is formed a drain opening J³ normally closed by a screw L screwing in the bottom of the fitting J and rendered tight by a suitable cap N, as indicated in Fig. 2.

The operation is as follows: The steam 70 passes from the boiler or other supply by way of the valve D into the upper end of the first or inlet section A of the radiator and from this inlet section the steam can pass into the intermediate sections C and also 75 into the overflow section B. The water of condensation effectually fills the inlet section A and the intermediate sections C up to the bottoms of the openings G, G' and any further water of condensation overflows through 80 the opening G² into the overflow section B, from which the water can flow by way of the pipe I into the compartment J' of the fitting J and by way of the pipe K back to the boiler.

85 By the arrangement described a uniform level of the water is had in the sections A and C of the radiator, while the section B is utilized as an overflow section from which the water of condensation can pass by way of the 90 pipe I, so as to insure a rapid heating of the water contained in the sections A and C. Thus by the arrangement described no sudden change of temperature of the water in the radiator takes place, as the same water 95 level in the radiator is maintained and the temperature of the water is raised evenly but very rapidly. The temperature is controlled by the operator manipulating the valve E in the supply pipe D in the usual 100 manner.

When it is desired to drain the sections A and C of water, it is only necessary for the operator to partly unscrew the screw L, so that the water of condensation can flow from 105 the compartment J² by way of the opening J³ into the compartment J' and to the pipe K, which conducts the water to the boiler.

It is understood that as the compartment J² is in communication with the lower end of 110 the inlet section A, and the sections A and C are connected with one another at the bot-

tom by the openings F, F', it is evident that all the water of condensation can be drained out of the said sections on unscrewing the screw L.

5 Having thus described our invention, we claim as new and desire to secure by Letters Patent:

1. A heating apparatus comprising a hot water radiator having a steam inlet section 10 in communication with a steam supply, an overflow section for the water of condensation, intermediate sections interposed between the inlet section and the overflow section, all of said sections being provided with 15 openings in their upper portions establishing communication between the sections, the bottoms of the several openings being on the same level, the said inlet section and the intermediate sections having openings in their 20 lower portions establishing communication between said sections, the openings being in horizontal alinement with each other, and a return water pipe leading from the overflow section and extending through the said openings in the lower part of the other sections. 25

2. A heating apparatus comprising a hot water radiator having a steam inlet section, an overflow section for the water of condensation, intermediate sections communicating 30 at their upper portions with the inlet section and the overflow section, the said inlet section and the intermediate sections having openings in the lower portions establishing communication between the said sections, a 35 return water pipe for carrying off the water of condensation from the overflow section, and a fitting on the lower end of the said steam inlet section into which drains the said return water pipe.

40 3. A heating apparatus comprising a hot water radiator having an inlet section in communication at its upper end with a steam supply, an overflow section, intermediate sections interposed between the said inlet 45 section and the said overflow section, the said inlet section and the said intermediate sections being in communication with one another at the bottom, and the said inlet section, the intermediate sections and the 50 overflow section being in communication with one another at the top, and a return water pipe leading from the bottom of the overflow section and extending through the openings connecting the intermediate sections 55 and the inlet section with one another at the bottom.

4. A heating apparatus comprising a hot water radiator having an inlet section in communication at its upper end with a steam supply, an overflow section, intermediate sections interposed between the said inlet section and the said overflow section, the said inlet section and the said intermediate sections being in communication with one 60 another at the bottom, and the said inlet 65

section, the intermediate sections and the overflow section being in communication with one another at the top, a return water pipe leading from the bottom of the overflow section and extending through the openings 70 connecting the intermediate sections and the inlet section with one another at the bottom, and a fitting on the lower end of the said inlet section and into which drains the said return water pipe. 75

5. A heating apparatus comprising a hot water radiator having an inlet section in communication at its upper end with a steam supply, an overflow section, intermediate sections interposed between the said inlet 80 section and the said overflow section, the said inlet section and the said intermediate sections being in communication with one another at the bottom, and the said inlet section, the intermediate sections and the 85 overflow section being in communication with one another at the top, a return water pipe leading from the bottom of the overflow section and extending through the openings connecting the intermediate sections and the 90 inlet section with one another at the bottom, and a fitting on the lower end of the said inlet section and into which drains the said return water pipe, the said fitting having a draining device for draining the water from 95 the said inlet section and the intermediate sections.

6. A heating apparatus comprising a hot water radiator having an inlet section in communication at its upper end with a steam 100 supply, an overflow section, intermediate sections interposed between the said inlet section and the said overflow section, the said inlet section and the said intermediate sections being in communication with one 105 another at the bottom, and the said inlet section, the intermediate sections and the overflow section being in communication with one another at the top, a return water pipe leading from the bottom of the overflow section and extending through the openings connecting the intermediate sections and the inlet section with one another at the bottom, and a fitting on the lower end of the 110 said inlet section and having two compartments one in communication with the said inlet section and the other forming a water discharge, and a draining device connecting the said compartments with each other. 115

7. A heating apparatus comprising a hot 120 water radiator having an inlet section in communication at its upper end with a steam supply, an overflow section, intermediate sections interposed between the said inlet section and the said overflow section, the 125 said inlet section and the said intermediate sections being in communication with one another at the bottom, and the said inlet section, the intermediate sections and the overflow section being in communication 130

with one another at the top, a return water pipe leading from the bottom of the overflow section and extending through the openings connecting the intermediate sections 5 and the inlet section with one another at the bottom, and a fitting on the lower end of the said inlet section and having two compartments, one in communication with the said inlet section and the other forming a water 10 discharge, and a draining device connecting the said compartments with each other, the said water return pipe discharging into the water discharge compartment.

8. A heating apparatus comprising a hot 15 water radiator having a steam inlet section, an overflow section, intermediate sections in communication with the inlet section and the overflow section, a return water pipe for carrying off the water of condensation from 20 the said overflow section, and a fitting on the

said steam inlet section and having a discharge compartment to which the said return water pipe leads, and a drainage compartment in communication with the inlet section and the intermediate sections of the 25 radiator, the drainage compartment being provided with a drain opening establishing communication with the discharge compartment, means for normally closing said drain opening, and a pipe leading from the discharge compartment.

In testimony whereof we have signed our names to this specification in the presence of two subscribing witnesses.
